[57] CLAIM

The ornamental design for a coilable measuring blade for top reading coilable rules, as shown.

DESCRIPTION

FIG. 1 is a plan view of one face of a coilable measuring blade showing my new design; and
FIG. 2 is a plan view of the other face of the coilable measuring blade.

The blade is shown broken away in FIGS. 1 and 2 to indicate indeterminate length.

FIG. 1

FIG. 2
